UNITED STATES PATENT OFFICE.

FREDERICK W. LEE, OF BALTIMORE, MARYLAND, AND LARS O. GRONDAHL, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 27, 1926. Serial No. 144,482.

Our invention relates to railway traffic controlling apparatus, and particularly to apparatus of the type wherein alternating current is periodically supplied to the track rails for the control of traffic governing mechanism which is responsive to such periodic supply of alternating current but not to the continuous supply of such current.

One form of apparatus of the character referred to is disclosed and claimed in application for Letters Patent of the United States filed by C. S. Snavely on May 29, 1926, Serial No. 112,491. In the apparatus disclosed in that application, when a section is occupied by a train and the next section in advance is unoccupied, alternating currents of two different frequencies are alternately applied to the track rails, and the train-carried apparatus is tuned to respond to one of these currents but not the other. This tuning is usually accomplished by an electric filter, but we have found that under some conditions the filter may respond to what we term "shock excitation", that is, when an alternating current is suddenly applied at its full value to the track rails, the filter receives an impulse which causes it to oscillate at its particular frequencies and so to falsely apply voltage to the train-carried apparatus, and this may be true even though the current which is abruptly applied is the current to which the filter is not tuned.

One feature of our invention is the provision of means for preventing sudden application of current to the track rails, that is, means for delaying the increase of the current to its full value when the current is applied.

We will describe one form of apparatus embodying our invention, and will then point out the novel features thereof in claims.

The accompanying drawing is a diagrammatic view showing one form of apparatus embodying our invention.

Referring to the drawing, the reference characters 1 and 1^a designate the track rails of a railway along which traffic normally moves in the direction indicated by the arrow. These rails are divided into track sections of which only one section C—D is shown in the drawing. Located at the exit end of section C—D are two transformers E⁶⁰ and E¹⁰⁰, the secondaries 11 and 9 of

which are connected across the rails 1 and 1^a. The primary 10 of transformer E⁶⁰ is at times supplied with alternating signaling current from the secondary 12 of a transformer T⁶⁰, the primary 13 of which is constantly connected with a source of alternating current which is not shown in the drawing. Similarly, the primary 8 of transformer E¹⁰⁰ is at times supplied with alternating current from the secondary 14 of a transformer T¹⁰⁰, the primary 15 of which is constantly connected with a source of alternating current not shown in the drawing. The currents supplied to the transformers T differ in frequency, and, as an example, the current supplied to transformer T⁶⁰ may be 60 cycles per second, and the current supplied to transformer T¹⁰⁰ may be 100 cycles per second.

The supply of current to the transformers E is controlled by a relay G, which I will term a "coding" relay, and this relay is in turn controlled by a track relay F which is connected across the rails at the entrance end of section C—D and is responsive to the 60 cycle current supplied to these rails by transformer E⁶⁰. The coding relay G is provided with a circuit which passes from terminal B of a suitable source of current, through back contact 3 of track relay F, winding of relay G, and back contact 4 of relay G to terminal O of the same source of current. It will be seen, therefore, that when section C—D is unoccupied and track relay F is energized, relay G will be at rest in its de-energized condition, but that when track relay F is de-energized the coding relay G will be alternately energized and de-energized, due to the fact that its back contact 4 is included in the circuit for its winding.

The reference character H⁶⁰ designates a reactor having a winding 7 included in the primary circuit for transformer E⁶⁰. This reactor also has a winding 6 which is at times energized by a battery 16 through back contact 5 of coding relay G. The reference character H¹⁰⁰ designates a similar reactor having a winding 7 included in the primary circuit for transformer E¹⁰⁰, and a winding 6 which is at times energized from battery 16 through front contact 5 of relay G. Each of these reactors H is so designed that when its winding 6 is de-energized the

reactance of winding 7 is so high that substantially no current is furnished to the associated transformer E, whereas when winding 6 is energized from battery 16, the core of the reactor is saturated so that winding 7 offers substantially no reactance to the flow of current to the associated transformer E. A resistance 17 is connected across winding 6 of reactor H⁶⁰, and a similar resistance 18 is connected across winding 6 of reactor H¹⁰⁰.

When section C—D is unoccupied and the back contact 5 of relay G is closed, winding 6 of reactor H⁶⁰ is energized so that winding 7 of this reactor offers little reactance to the flow of current from transformer T⁶⁰, and, consequently, 60 cycle current is constantly supplied to the rails of the section and track relay F is energized. The circuit for winding 6 of reactor H¹⁰⁰ is then opened, so that substantially no 100 cycle current is supplied to the track rails. When a train enters section C—D, it opens relay F thereby starting the operation of coding relay G, so that the windings 6 of reactors H⁶⁰ and H¹⁰⁰ are alternately energized. The result of this is the alternate supply of 60 cycle and 100 cycle current to the rails of section C—D. Each time that a winding 6 becomes energized, however, a brief interval elapses before the reactance of the associated winding 7 is reduced to its final value, and so a brief interval elapses before the corresponding alternating current builds up to its final value in the track rails. Each time that the back point of contact 5 opens, the current in winding 6 of reactor H⁶⁰ dies down gradually through resistance 17, so that a brief interval of time elapses before the reactance of associated winding 7 builds up to its maximum value, with the result that the 60 cycle current dies down gradually thus avoiding shock. Resistance 18 performs a similar function when the front point of contact 5 opens.

Although we have herein shown and described only one form of apparatus embodying our invention, it is understood that various changes and modifications may be made therein within the scope of the appended claims without departing from the spirit and scope of our invention.

Having thus described our invention, what we claim is:

5. 1. In combination with the track rails of a railway, a source of alternating current connected with said rails through a reactor, and means for periodically varying the effect of said reactor.
6. 2. In combination with the track rails of a railway, a source of alternating current connected with said rails through a reactor,

a periodically operating contact, and means controlled by said contact for periodically varying the effect of said reactor.

65

3. In combination with the rails of a railway track, a source of alternating current connected therewith, a reactor having a first winding interposed between said source and said rails, a second winding on said reactor 70 effective when energized to substantially neutralize the reactance of the first winding, and means for periodically energizing said second winding.

4. In combination with the rails of a rail- 75 way track, a source of alternating current connected therewith, a reactor having a first winding interposed between said source and said rails, a second winding on said reactor effective when energized to substantially 80 neutralize the reactance of the first winding, means for periodically energizing said sec- ond winding, and a resistance connected across said second winding to cause the current in such winding to die down gradually 85 when the winding becomes de-energized.

5. In combination with the track rails of a railway, a source of alternating current connected therewith through a reactor, and means for periodically saturating the core 90 of said reactor.

6. In combination with the track rails of a railway, a source of alternating current of one frequency connected therewith through a reactor, a second source of alternating 95 current of a different frequency connected with said rails through a second reactor, and means for alternately neutralizing the effect of said reactors.

7. In combination with the track rails of 100 a railway, a source of alternating current connected therewith, a reactor having a first winding interposed between said source and said rails, a second winding on said reactor effective when energized to saturate the core 105 of the reactor, and a circuit for said second winding including a source of current and a periodically operated contact.

8. In combination with the track rails of 110 a railway, a source of alternating current connected therewith, a reactor having a first winding interposed between said source and said rails, a second winding on said reactor effective when energized to saturate the core 115 of the reactor, a circuit for said second winding including a source of current and a periodically operated contact, and a resistance connected across said second winding to cause the current in such winding to die down gradually when said contact opens.

In testimony whereof we affix our signatures.

FREDERICK W. LEE.
